ELECTRIC WARP STOP MOTION

Richard Greenleaf Turner, Worcester, Mass., assignor to Crompton & Knowles Loom Works, Worcester, Mass., a corporation of Massachusetts

Application July 5, 1935, Serial No. 29,769

12 Claims. (Cl. 139—351)

This invention relates to improvements in warp stop motions and particularly the means for finding the fallen drop wire on electrical warp stop motions.

5 Electrical warp stop motions customarily employ a relatively large group of light thin drop wires each effective when fallen to close a circuit including a loom stopping electromagnetic device. It is a matter of practical difficulty to 10 determine the location of the fallen drop wire, particularly in electrical motions where there is ordinarily no moving part to cooperate with the fallen drop wire. Warp stop motions of electrical type customarily employ contact bars including two electrodes insulated from each other and arranged to be electrically connected by the fallen drop wire to close a circuit. It is an important 15 object of my present invention to provide means dependent upon the heat developed by passage of current through the fallen drop wire to indicate the location of the latter.

In order to make effective use of the heat principle I employ a drop wire made of two component parts having different co-efficients of expansion. 25 I may, for instance, make the drop wire out of sheet material one side of which is formed of sheet brass while the other side is formed of sheet steel, the two parts being secured together in any approved manner so that in effect these two parts 30 form a single drop wire. The wire thus formed will tend to curve when heated, the greater expansion of one metal deforming or bending the drop wire to give a visual indication of its position.

35 In the specific form set forth hereinafter I employ a drop wire of the type which has gone into general use with a well-known form of electrical warp stop motion set forth more particularly in patent to Payne No. 1,852,024. The drop wire for that type of warp stop motion has in the upper 40 part thereof a slot to receive a contact bar which cooperates with a pair of cam shaped lobes arranged to connect electrically the two electrodes of the contact bar. The current flows from the 45 lobes partly through the upper and partly through the lower part of the drop wire, tending to heat and therefore curve a considerable length of the wire.

In order to prevent burning of contact bars and 50 drop wires it is customary in warp stop motions to break the circuit by the stopping of the loom. Any heating which might result in the drop wire in the short interval between the falling of the drop wire and the subsequent moving of the 55 shipper handle to stopping position might be lost

before the weaver has an opportunity to visit the loom, and it is a further object of my present invention to provide a manually controlled heating circuit to include the fallen drop wire. By means of this circuit the weaver can establish a current through the fallen drop wire and by 5 watching the bank of drop wires will be able to detect the lateral movement or disturbance in drop wires caused by the curvature of the one which is down. As a matter of practical convenience the manually controlled circuit omits the electro-magnetic device so that a repeated indication is eliminated. This latter feature also results in removing the resistance of the electro-magnetic device from the heating circuit with 10 resultant increased current which will cause the fallen drop wire to bend in a minimum of time.

With these and other objects in view which will appear as the description proceeds, my invention resides in the combination and arrangement of parts hereinafter described and set forth in the 15 claims.

In the accompanying drawing, wherein a convenient embodiment of my invention is set forth,

Fig. 1 is a rear elevation of a portion of a warp stop motion having my drop wires applied, and showing one of the drop wires curved by heat to indicate its location,

Fig. 2 is an enlarged section on line 2—2, Fig. 1, showing the drop wire in fallen position,

Fig. 3 is an end elevation taken in the direction of arrow 3, Fig. 2, showing the drop wire fallen and straight before the heating circuit has been manually closed in full lines and indicating in dotted lines the curvature resulting in the drop wire when the heating circuit is closed, and

Fig. 4 is a diagrammatic view of the electric circuits which I may employ.

Referring to the drawing, I have indicated a contact bar 10 having an outer electrode 11 with a longitudinal rib 12 and bent along its top and bottom edges at 13. Located within the outlines of electrode 11 is a second electrode 14 insulated therefrom and having a contacting surface 15 which is horizontally opposite the rib 12. The bar 10 may be supported by a holder 16 which serves also to support separator bars 17. The inner electrode may project as at 18 to have contact with a wire 19 electrically connected to means for stopping the loom when the two electrodes are in electrical connection.

The drop wire 25 may be of the form shown in Fig. 2 and has an upper slot 26 through which the contact bar passes and into which lobes project. The lower part of the drop wire may have

an open slot 28 by means of which the wire is dropped on a warp thread W extending across and positioned by the separator bars 17.

Normally, the drop wire will be in elevated position so that neither of the lobes 27 is in operative relation with respect to the electrode, but when a warp thread breaks its drop wire falls to the position shown in Fig. 2, and the camming interaction between the rib 12 and one of the lobes moves the other lobe against the insulated electrode. Thereupon current flows from one of the electrodes through that part of the wire surrounding the slot 26 to the other electrode to effect loom stoppage. The matter thus far described may be substantially the same as set forth in the aforesaid patent to Payne.

As already indicated the difficulty of locating the fallen drop wire is considerably increased when there are several banks of drop wires similar to those set forth in Fig. 2, and the difficulty is further increased by the varied positions of the drop wires when the loom is equipped with a number of harness frames which may be in a variety of vertical positions when the loom stops. In order to locate the drop wire I propose to make the same of two dissimilar metals one of which has a co-efficient of expansion considerably greater than the other. As shown in Fig. 3, for instance, the drop wire may be made of a thin strip of steel 30 secured to a second strip 31 which may be formed of brass or copper. These two sheets are fused or otherwise secured together and are similar to commercial products employed in the manufacture of thermostats. The drop wires will ordinarily be in close relationship as suggested in the greater part of Fig. 1 and when current flows from one lobe 27 to the other it must pass through both metallic parts of the drop wire, resulting in an unequal expansion which bows the drop wire, as shown in Fig. 1. Ordinarily a drop wire will be straight as shown in full lines in Fig. 3, but when current flows therethrough it will curve to the dotted line position and serve to spread or disturb adjacent drop wires as suggested in Fig. 1, thereby indicating the location of the broken warp thread.

A weaver ordinarily takes care of a group of looms and may not be near a loom when it is stopped by a warp fault, and furthermore, it is desirable to break the circuit through the warp stop motion as soon as the loom stops to prevent burning of the drop wires and to reduce fire hazard. In order to take these conditions into account I provide electric circuits shown in Fig. 4 suitable for stopping the loom and also for enabling the weaver to reestablish a circuit through the fallen drop wire. The shipper handle 40 of the loom is indicated in full lines in the running position and when in this position is in electric contact with a contact 41 set forth diagrammatically in Fig. 4. A manually operable switch S comprises a vertical stem 45 urged upwardly by a compression spring 46 and passing through a housing indicated diagrammatically at 47. The spring coacts with part of the housing to urge the stem upwardly so that the bridge or cross bar 48 moving with the stem will normally have yielding contact with a pair of upper electrodes 49 and 50, respectively. There are two other electrodes 51 and 52 located beneath the first described pair also capable of electrical connection by means of bridge

When the loom is running normally the contacts 49 and 50 will be connected by the bridge and upon occurrence of a warp fault current will flow in the following stopping circuit: ground G, wire 60, shipper handle 40, contact 41, wire 51, electro-magnetic device 62, which when energized effects loom stoppage, wire 63, source of electric power, such as a transformer 64, wire 19, insulated electrode 14, the fallen drop wire 25, inclosing electrode 11, wire 65, electrode 49, 10 bridge 48, electrode 50, and wire 66 to the ground. Closure of this circuit will operate to move the shipper handle from the full to the dotted line position shown in Fig. 4 when the loom stops, thereby breaking the circuit with no appreciable heating of the drop wire.

When the weaver arrives at the loom the stem 45 may be moved downwardly manually so that the bridge assumes the dotted line position shown in Fig. 4, electrically connecting the electrodes 51 and 52, whereupon current will flow in the following heating circuit: transformer 64, wire 19, insulated electrode 14, the fallen drop wire 25, electrode 11, wire 65, wire 70, electrode 51, bridge 48, electrode 52, wire 67, and wire 63 25 back to the transformer. This heating circuit is maintained closed as long as needed to cause the requisite heating of the fallen wire.

The switch S is conveniently located in such a position that when being pressed the weaver 30 will have an opportunity to watch the drop wires and notice any jarring or disturbance which results from the bending of the fallen drop wire as the latter tends to assume the position indicated in dotted lines in Fig. 3. When the location of the warp fault is found the switch S is released and the spring around the stem reestablishes contact between electrodes 49 and 50. The second or heating circuit traced hereinbefore does not include the electro-magnetic device, the latter being purposely eliminated so that the resistance of the circuit is a minimum to permit heating of the drop wire in the shortest time possible. Upon cooling a fallen drop wire will assume its normally flat or straight position. 45

From the foregoing it will be seen that I have provided a simple form of drop wire for electrical warp stop motions so constructed that current passing through it will cause a change in the form thereof of sufficient extent to spread or 50 disturb adjacent drop wires to indicate the location of the broken warp thread. It will further be seen that I have provided a heating circuit supplementary to the normal stopping circuit and manually operable by the weaver after the 55 stopping circuit has been broken due to loom stoppage. While I have suggested two different metals of which the drop wire can be made, yet I do not wish to be limited to these metals inasmuch as the principles set forth herein depend 60 generally for their operation upon deformation of a fallen drop wire to indicate the location of the warp fault.

Having thus described my invention it will be seen that changes and modifications may be 65 made therein by those skilled in the art without departing from the spirit and scope of the invention and I do not wish to be limited to the details herein disclosed, but what I claim is:

1. In an electric warp stop motion, a contact 70 bar comprising two electrodes insulated from each other, and a drop wire capable of falling into contact with both electrodes upon occurrence of a warp fault and formed of two materials having different co-efficients of expansion 75

- to cause a deformation in the drop wire when current passes therethrough to indicate its location.
2. In an electric warp stop motion, a contact bar comprising two electrodes insulated from each other, and a drop wire capable of falling into contacting relation with respect to each electrode, the drop wire being formed of two substantially similar sheets secured together and each sheet having a co-efficient of expansion different from that of the other sheet, whereby current flowing through the drop wire will heat and deform the latter to give visual indication of its location.
3. In an electric warp stop motion, a contact bar comprising a pair of insulated electrodes, a drop wire normally out of electrical engagement with the electrodes but capable of falling to a position to connect the electrodes when the corresponding warp thread is broken, and means including a manually operative switch to establish a circuit including said switch and electrodes and the drop wire when fallen to cause a current to flow through the latter and heat the same, said drop wire constructed to undergo a change in the form thereof when heated by a current passing therethrough to indicate its location.
4. In an electrical warp stop motion, a contact bar comprising two electrodes insulated from each other, and a drop wire effective when the corresponding warp thread therefor is broken to move to contacting position with respect to the electrodes and thereby be rendered capable of having a current of electricity pass therethrough, the drop wire constructed of materials having dissimilar co-efficients of expansion to effect a deformation in the drop wire when heated to indicate its location.
5. In a loom, a warp stop motion contact bar comprising two insulated electrodes, a part to be moved from running to stopping position when the loom is stopped, a drop wire capable when heated of changing its form to indicate its location, means including the drop wire when in contact with the electrodes and also the electrodes defining a stopping circuit which is broken when said part moves from running to stopping position, a manually operated switch, and other means including said switch and fallen drop wire and constituting a heating circuit effective when closed to cause current to pass through said fallen drop wire and thereby heat the drop wire.
6. In a loom, a warp stop motion contact bar, a drop wire normally in raised position and capable when in fallen position of having an electric current pass therethrough by engagement with the contact bar, said drop wire effective when heated to undergo a change in form thereof to indicate its location, means including the fallen drop wire constituting a stopping cir-

cuit to effect loom stoppage, a manually closable switch, and other means including the switch and fallen drop wire constituting a heating circuit effective when closed by the switch to cause current to pass through the drop wire and heat the same to effect a change of form therein.

7. In an electrical warp stop motion, a drop wire having a slot formed therein, a pair of lobes extending into the slot, a contact bar passing through the slot and having two electrodes insulated from each other, the lobes effective when the drop wire is fallen to connect the electrodes electrically and permit passage of current from the electrodes through the drop wire, said drop wire formed of two materials having dissimilar co-efficients of expansion effective to subject the drop wire to a change in form when heated by current passing therethrough.

8. In an electrical warp stop motion, a drop wire having a slot therein, a contact bar passing through the slot and comprising two insulated electrodes, means to cause a drop wire when fallen to move into electrical connection with both electrodes to permit the current to flow through the drop wire, said drop wire formed of two materials having dissimilar co-efficients of expansion rendering the drop wire capable of undergoing an alteration in its form when heated by an electric current flowing therethrough.

9. In a loom, a warp stop motion contact bar comprising two electrodes insulated from each other, a drop wire effective when in fallen position to connect the electrodes electrically and be capable of transmitting an electric current from one electrode to the other, said drop wire effective when heated to undergo a change in form thereof, a stopping circuit including the fallen drop wire and electrodes to effect loom stoppage, a normally open switch, and other means including the fallen drop wire and electrodes constituting a heating circuit to be established when the switch is closed for the purposes of causing current to flow through the drop wire and heat the same.

10. An electric warp stop motion drop wire formed of two parallel strips of metal secured to each other throughout their length and having dissimilar co-efficients of expansion.

11. An electrical warp stop motion drop wire formed of two similar sheets of material secured to each other, each sheet having a co-efficient of expansion different from that of the other sheet.

12. An electrical warp stop motion drop wire having a slot therein into which project lobes at points intermediate the ends of the slot, said drop wire formed of parallel strips of metal secured to each other throughout their length and having dissimilar co-efficients of expansion and capable of conducting current from the lobe toward each end of the slot.

RICHARD GREENLEAF TURNER.
